(57) **CLAIM**

The ornamental design for a display screen or portion thereof with a graphical user interface, as shown and described.

DESCRIPTION

FIG. 1 is a front view of a display screen or portion thereof with a graphical user interface showing the present design; FIG. 2 is a front view of another embodiment of a display screen or portion thereof with a graphical user interface showing the present design; FIG. 3 is a front view of another embodiment of a display screen or portion thereof with a graphical user interface showing the present design; FIG. 4 is a front view of another embodiment of a display screen or portion thereof with a graphical user interface showing the present design; FIG. 5 is a front view of another embodiment of a display screen or portion thereof with a graphical user interface showing the present design; FIG. 6 is a front view of another embodiment of a display screen or portion thereof with a graphical user interface showing the present design; FIG. 7 is a front view of another embodiment of a display screen or portion thereof with a graphical user interface showing the present design; and, FIG. 8 is a front view of another embodiment of a display screen or portion thereof with a graphical user interface showing the present design. The broken lines show an electronic device with a display screen and form no part of the claimed design.

1 Claim, 8 Drawing Sheets
